RAILWAY TRAFFIC CONTROLLING APPARATUS

Original Filed April 22, 1931

UNITED STATES PATENT OFFICE

2,042,904

RAILWAY TRAFFIC CONTROLLING
APPARATUS

Ronald A. McCann, Swissvale, Pa., assignor to
The Union Switch & Signal Company, Swiss-
vale, Pa., a corporation of Pennsylvania

Application April 22, 1931, Serial No. 532,026
Renewed March 29, 1932

5 Claims. (Cl. 246—41)

My invention relates to railway traffic controlling apparatus, and particularly to apparatus of the type involving track circuits. One feature of my invention is the provision, in apparatus of this character, of means for preventing improper operation in the event that when a light engine or a gasoline car passes from one section into another the track relay for the first section closes before the track relay for the second section opens.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the rails of a stretch of railway track along which traffic moves in both directions. These rails are divided by insulated joints 2 to form blocks C—D, D—E, etc., and each block is further divided by insulated joints 2^a to form at least two track sections. Each section is provided with a track circuit comprising a battery 3 and a track relay T. Traffic moving toward the right is governed by signals SC, SD, and SE, etc., each of which, as here shown, is in the form of a light signal having the usual proceed, caution and stop lamps G, Y and R, respectively.

Associated with each signal SC and SD is a polarized home relay H, a repeater relay R, and a stick relay X, and these relays, in the form of apparatus shown herein, are controlled in accordance with what is known as "Absolute permissive block signaling".

Each relay R is provided with a circuit which passes from terminal B of a suitable source of current, through front contact 16 of the associated relay H, and the winding of relay R to terminal O of the same source of current. It follows that each relay R is energized when the associated relay H is energized in either direction, and is deenergized when the associated relay H is deenergized. Each relay R has both slow pickup and slow releasing characteristics.

Relay HC is provided with a circuit which passes from terminal B, through front contact 6 of relay HD, front point of contact 7 of relay RD, front contact 8 of track relay TD1, front contact 9 of track relay TC, the winding of relay HC, and the front point of contact 10 of relay RD, to terminal O. When this circuit is closed, relay HC is energized by current of normal polarity, so that its polar contact 21 is swung to the left. When relays HD and RD are both

deenergized and relay XD is energized, an auxiliary circuit for relay HC is closed, which circuit is from terminal B, through front contact 11 of relay XD, back point of contact 10 of relay RD, winding of relay HC, contacts 9 and 8 of track relays TC and TD1, and back point of contact 7 of relay RD, to terminal O. When this circuit is closed, current of reverse polarity is supplied to relay HC, so that the polar contact 21 of this relay is swung to the right.

Relay HD is controlled by contacts 9 and 8 of track relays TD and TD1, and by pole-changing contacts 12 and 15 of home relay HE. The control is such that when block D—E is unoccupied, relay HD will be energized in the normal or the reverse direction, according as relay HE is energized or deenergized.

Relay XD is provided with a pick-up circuit which passes from terminal B, through back contact 17 of track relay TD, front point of contact 18 of relay RD, and the winding of relay XD, to terminal O. This relay is also provided with a stick circuit which passes from terminal B, through back point of contact 18 of relay RD, front contact 19 of relay XD, and the winding of relay XD, to terminal O. The circuits for the control of stick relay XC are similar to those for the control of relay XD.

The lamps of signal SD are controlled in the usual manner by the contacts of relays HD and RD. That is to say, when relay HD is energized in the normal direction, lamp G will be lighted by virtue of a circuit which includes the front point of contact 20 of relay RD and contact 21 of relay HD in the normal position. When relay HD is energized in the reverse direction, lamp Y will be lighted by virtue of a circuit which includes the front contact 20 of relay RD and contact 21 in the reverse position. When relay RD is deenergized, lamp R will be lighted by virtue of a circuit which includes the back point of contact 20. The circuits for the signal SC are similar to those for signal SD.

The operation of the apparatus is as follows: When a train moving toward the right enters section C—4, it will open track relay TC, thereby opening the circuit for relay HC, and this, in turn, will open the circuit for relay RC. The closing of back contact 17 of track relay TC will close the pick-up circuit for relay XC, and this relay will subsequently remain energized as long as relay RC is open. When the train enters section 4—D it will deenergize relay TD1, but that will cause no other change in the condition of the apparatus. When the train enters section D—5,

it will open track relay TD, thereby opening relays HD and RD and closing relay XD. When the rear end of the train has passed entirely out of the section 4—D, relay HC will become energized in the reverse direction, thereby causing the caution lamp Y of signal SC to become lighted. When the train passes into section 5—E, it will cause no change in the condition of the apparatus, except to deenergize relay TE1. When 10 the train passes point E, the caution lamp Y of signal SD will become lighted, and the proceed lamp of signal SC will become lighted.

I will now assume that while a short vehicle, such as a light engine or gasoline electric car, 15 is passing the point D, track relay TD1 closes before track relay TD opens. This will permit relay HC to be momentarily energized in the normal direction, and if relay RC were a quick pick-up relay, the proceed lamp G of signal SC would be momentarily lighted. Inasmuch as 20 this relay RC is characterized by requiring a time interval to close its front contacts after the relay becomes energized, this relay will not close during the brief interval of time between 25 the closing of track relay TD1 and the opening of track relay TD, and so the proceed lamp G of signal SC will not be momentarily lighted. That is to say, lamp R of this signal will remain lighted until relay HC becomes energized 30 in the reverse direction to cause lamp Y to become lighted.

Furthermore, when a short vehicle passes point 5, relay TD may close before relay TE1 opens, and this will allow relay HD to be momentarily energized. If relay RD were a quick pick-up relay, it would open its back contacts 35 during this brief energization of relay HD, and would thereby open the stick circuit for relay XD, with the result that the auxiliary circuit 40 for relay HC would be opened and would remain open after relay TE1 opens. This would extinguish the caution lamp Y of signal SC, and would light the stop lamp R of this signal. Inasmuch as relay RD has a slow pick-up characteristic, it 45 will not open its back contacts during the brief energization of relay HD referred to above, and so the stick circuit for relay XD will not be opened.

Owing to the slow-releasing characteristic of 50 each relay RC and RD, the associated signal is prevented from momentarily giving a stop indication during the reversal of the polar contact 21 of the associated relay H, but this is not a novel feature of the present invention.

55 Although I have herein shown and described only one form of apparatus embodying my invention, it is understood that various changes and modifications may be made therein within the scope of the appended claims without departing 60 from the spirit and scope of my invention.

Having thus described my invention, what I claim is:

1. In combination, a block of railway track 65 divided to form two track sections, a track circuit including a track relay for each section, means including a home relay for governing traffic in one direction through said block, a circuit for said home relay including front contacts of both of said track relays, a repeater relay controlled by a front contact of said home 70 relay and having slow pick-up and slow releasing characteristics, a stick relay; control means for said stick relay delaying a change in the condition of the relay during the pickup time 75 of said repeater relay to prevent such change

during a brief simultaneous energization of both said track relays and comprising a pick-up circuit for said stick relay including a back contact of the track relay first opened by a train moving in said one direction entering said block 5 as well as a front contact of said repeater relay, and a stick circuit for said stick relay including a back contact of said repeater relay; and means controlled by said stick relay for governing traffic moving in said one direction approaching said 10 block.

2. In combination, a stretch of railway track divided to form a rear and a forward block, track circuits including track relays for said blocks, a home relay for the forward block controlled 15 by the track relays for such block, a first repeater relay controlled by said home relay, a stick relay for said forward block, means for energizing said stick relay when a vehicle enters the forward block from the rear block and for 20 keeping it energized as long as the train occupies the forward block, a second home relay for the rear block, means operating when the rear block is unoccupied to energize said second home 25 relay in normal direction if said first repeater relay is closed and in reverse direction when said first repeater relay is open and said stick relay is closed, a second repeater relay for said rear block controlled by said second home relay and having slow pick-up and slow releasing characteristics, proceed and caution indication 30 circuits for said rear block controlled by a front contact of said second repeater relay, and a stop indication circuit for said rear block controlled by a back contact of said second repeater relay, whereby the slow pick-up characteristic of said second repeater relay retains said stop indication circuit closed after the energization of said second home relay upon the passage of a train 35 from said rear block into said forward block until 40 after said first home relay has released.

3. In an absolute permissive block signaling system for railroads, the combination with two successive sections of track, of a track relay for each section, a line relay associated with an intermediate signal and controlled by both of said track relays, a repeater relay having a winding and front and back contacts operated by said winding which contacts are slow to close and open respectively when the winding becomes 50 energized, a circuit including said winding and a front contact of said line relay, and a directional stick relay having a pickup circuit including a front contact of said repeater relay and a stick circuit including a back contact of said repeater relay whereby said directional relay is prevented from becoming energized, or if energized, is prevented from becoming released, in the event that one of said track relays picks up 55 before the other releases, due to the movement of a train from one of said track circuits to the other, and energizes said line relay for a period longer than the usual pickup time of a quick acting relay.

4. In an absolute permissive block signaling 65 system for railroads, the combination with the track relays of two adjacent track sections of said system, the usual line relay controlled by front contacts of said track relays, and the usual directional stick relay, a repeater relay having 70 a winding and front and back contacts operated by said winding which contacts are slow to close and open respectively when the winding becomes energized, a circuit including said winding and a front contact of said line relay, a pick-up and 75

a stick circuit for said directional stick relay, each including a back contact of one of said track relays, said pickup circuit also including the front contact of the repeater relay, and a 5 second stick circuit for said directional relay including the back contact of the repeater relay, whereby a change in the condition of said directional relay is delayed after an energization of said line relay until the expiration of the slow 10 pickup period of said repeater relay.

5. In a railway signaling system, in combination with two consecutive block sections each having track circuits provided with track relays, a line relay for the advance section controlled 15 by the track relays of such section; a line relay for the rear section controlled by the track re-

lays of such section and by the line relay for the advance section; a repeater relay having a winding included in a circuit with a front contact of the line relay for the rear section and contacts which are slow to operate when the winding becomes energized, and a signal for the rear section controlled by contacts of said repeater relay, whereby a change in the indication of said signal is delayed during the slow pickup period of said repeater relay in the event the 10 line relay for the rear section picks up before the line relay for the advance section releases due to the movement of a train from the rear section to the advance section.
